J. K. WILKENS

DEMOUNTABLE RIM

Filed Oct. 27, 1922

FIG. 1.

FIG. 2.

FIG. 3.

Inventor

J. K. Wilkens.

By *J. Randolph Jr.* Attorney

UNITED STATES PATENT OFFICE.

JACOB K. WILKENS, OF MUSCATINE, IOWA.

DEMOUNTABLE RIM.

Application filed October 27, 1922. Serial No. 597,317.

To all whom it may concern:

Be it known that I, JACOB K. WILKENS, a citizen of the United States, residing at Muscatine, in the county of Muscatine and State 5 of Iowa, have invented certain new and useful Improvements in Demountable Rims; and I do hereby declare the following to be a full, clear, and exact description of the invention, such as will enable others skilled 10 in the art to which it appertains to make and use the same.

The invention relates to demountable rims and more particularly to such rims which comprise sections, whereby to facilitate the 15 mounting and dismounting of pneumatic tires.

Specifically considered, the invention relates to a demountable rim embodying sections of unequal length and which sections 20 when assembled are made secure by means constructed in accordance with the present invention.

Other objects and advantages will be apparent and suggest themselves as the nature 25 of the invention is understood.

While the drawings illustrate an embodiment of the invention it is to be understood that in adapting the same to meet different conditions and requirements, various changes 30 in the form, proportion and minor details of construction may be resorted to without departing from the nature of the invention.

Referring to the accompanying drawings forming a part of the application,

Figure 1 is a perspective view of the adjacent ends of a sectional rim provided with locking means embodying the invention, said ends being separated.

Figure 2 is a longitudinal section, and 40 Figure 3 a transverse section.

Corresponding and like parts are referred to in the following description and designated in the several views of the drawings by like reference characters.

The numerals 1 and 2 designate adjacent ends of sections comprising a demountable rim which may be of any usual construction. The end 1 is provided with an opening 3 adjacent the joint formed between the two 50 ends when the latter are assembled. A U-

shaped keeper 4 is provided upon the inner or rear side of the end 1 in the rear of the opening 3 and the opposite side members are undercut, as shown most clearly in Figure 3. The open side of the keeper 4 is adjacent the 55 opening 3. A locking slide 5 is mounted within the keeper 4 and is slidable through the open side thereof across the opening 3 to secure the joint formed between the ends of the adjacent rim sections. A tongue 6, 60 carried by the section 2, projects beyond the end thereof a distance to overlap the end of the section 1 and is provided at its outer end with an offstanding projection or lip 7 which enters the opening 3 and is retained therein 65 by the locking slide 5 which is moved outwardly so as to overlap the element 7. The part 6 may be formed with the section 2 or may be attached thereto in any manner. A screw 8 or like fastening secures the locking slide 5 when projected into locking engagement with the lip or projecting part 7. When the screw 8 is removed, the locking slide 5 may be withdrawn into the keeper 4 so as to clear the opening 3 and thereby admit of separating or placing the sections 1 and 2 in position. The several parts, such as the keeper 4, locking slide 5 and tongue 6, appear on the inner or rear side of the rim 70 so as to occupy a position adjacent the felly 80 band of the wheel when the rim is in position thereon.

What is claimed is:

Means for securing the separable ends of a demountable rim, the same comprising an 85 opening formed in one of the ends, a substantially U-shaped keeper on the end provided with the opening and having the open side adjacent the said opening, a locking slide mounted in the keeper and adapted to 90 be moved to extend over said opening, a tongue projecting from the companion end of the rim and having a projection or lip adapted to enter the said opening and retained therein by the locking slide, and 95 means for securing the locking slide in operative position.

In testimony whereof I affix my signature.

JACOB K. WILKENS.
